UNITED STATES PATENT OFFICE.

GEORGE B. NORRIS, OF COLUMBUS, OHIO, ASSIGNOR, BY MESNE ASSIGNMENTS, TO THE
JEFFREY MANUFACTURING COMPANY, A CORPORATION OF OHIO.

MINING-MACHINE.

1,215,692.

Specification of Letters Patent. Patented Feb. 13, 1917.

Application filed December 18, 1915. Serial No. 292,372.

To all whom it may concern:

Be it known that I, GEORGE B. NORRIS, a citizen of the United States, residing at Columbus, in the county of Franklin and State of Ohio, have invented certain new and useful Improvements in Mining Machines, of which the following is a specification, reference being had therein to the accompanying drawing.

10 In the mining of coal—especially where the veins are thin or low, much difficulty is experienced in moving the under-cutting machines from one position to another in the chamber where the cuts are being made, owing to the weight of the machines, the want of head room and other causes. My invention has for its object to provide improved means supplemental to the usual cutter feeding mechanism by which a mining machine may be shifted from one position to another within the chambers of the mine by means of power obtained directly from the motor of the machine, and while it is particularly adapted for shifting a machine 20 designed for use upon low veins of coal, it is not limited in its useful applications to machines of this character. Considered more specifically, the object of my invention is to provide a mining machine having an improved arrangement of cable winding drums and cable guides whereby the machine may be moved by means of cables.

25 Figure 1 is a top plan view of a breast mining machine provided with my invention, the machine being represented as supported upon a transporting truck. Fig. 2 is a side view of the parts represented in Fig. 1. Fig. 3 is a side view of the mining machine separate from the truck. Fig. 4 is a diagram of a mine illustrating the method of using the invention.

In the drawings, A, A', A², and A³ represent four chambers of a mine, B the gangway connecting them, and C, C', C², and C³ the entries to the several chambers. Within the gangway and entries is arranged a track system D. The vertical dimensions of the gangway and entries are represented as being greater than the like dimensions of the chambers, the mining machine when within the chamber resting upon a bench, the level of which is above that of the track.

E designates, as a whole, a truck adapted to be used in transporting the mining machine, (which is designated, as a whole, by

F) from one position within the mine to another. The truck is represented as having the wheels e, the frame work e' and a suitable support e², on which the mining machine is adapted to rest.

In its general features this truck may correspond with the truck represented in Reissue Patent 11,540 to H. B. Dierdorff, dated May 26th, 1896, although the one illustrated differs from that shown in said patent in that it is constructed so as to support the machine at a relatively high level above the track in order that the mining machine may be easily moved off the car and on to the bench or floor of the chamber when the cars are run into the entry.

The mining machine herein illustrated and to which my invention is applied is of the breast type, having a stationary or bed frame and a movable frame supported thereupon carrying the cutters and the motor. It is in its general features of construction similar to the mining machine illustrated in Patent 684,356 to H. B. Dierdorff, dated October 8, 1901, to which patent reference is made for details of construction.

The main or bed frame of the mining machine consists essentially of the side bars 2, the cross bars 3, of suitable number, and the shoes 4 upon which the machine rests when in working positions. Within this frame is mounted the movable cutter frame, which is indicated in a general way by 5. Around this cutter frame there travels an endless cutter chain 5². At the rear, the cutter frame is provided with a platform 6, upon which is supported the motor 7, an electric motor being represented, in a general way, in the drawings. The motor operates to drive the cutter chain and to move the cutter frame backward and forward relatively to the main frame in the usual manner, it being herein unnecessary either to show in detail the gearing for effecting these movements or to describe it at length. It should, however, be noted that this gearing comprises a transverse shaft a mounted on the movable cutter frame and provided at its ends with pinions b which mesh with the racks c secured to the main frame. Two sets of gearing are provided for connecting the shaft a with the motor, one set 9 serving to drive the shaft in one direction to feed the motor frame forward, and the other set d serving to drive the shaft in the oppo-

site direction to move the cutter frame backward. By means of a clutch *m* the shaft *a* can be connected with either set of gearing or can be entirely disconnected from both. 8 indicates a transverse shaft mounted in the rear part of the stationary or bed frame of the mining machine and arranged to be connected with the motor 7 by the train of gearing 9, when the cutter and motor-carrying frame of the machine is drawn back to its extreme position. The gearing 9 comprises a worm or gear wheel rotatable on the shaft *a* and there is provided a gear wheel *f* on the shaft 8 in position to mesh with this gear wheel of the gearing 9 when the cutter frame is in its rear position. Upon one end of this shaft there is secured a sprocket or chain wheel 10 arranged to be connected by a chain or belt 11 with a wheel 12 upon one of the axles of the supporting car or truck E. Through this train of mechanism the truck is propelled from the motor of the mining machine when the latter is in place upon the car. There are also secured upon the cross shaft 8 a pair of winches 13, one at either end of the shaft. 14, 14 are grooved guide pulleys mounted upon vertically disposed supporting pins or studs 15, which in turn are carried by brackets 16. There is one of these brackets at each side of the machine and it is preferably supported upon and adjustable along a side bar 2 of the main frame. 17, 17 represent jacks or posts adapted to be secured in place in one position or another within the mine chamber, and adapted to be easily set in place in whatever positions it may be desirable they should occupy. 18 indicates a rope adapted to be secured at one end to one of the jacks or posts 17 and to be wrapped around one of the winches 13, passing in its course one of the grooved pulleys 14, if this should be found desirable to give direction to the rope and cause it to work properly.

With this description, an understanding of the manner of working my invention may be had, reference being made to the diagrammatic figure or view—Fig. 4. 50 In chamber A the mining machine is represented as being still supported upon the truck, which has been run into entry C, and close up to the edge of the bench of the chamber. The first operations are to disconnect the motor from the driven axle of the truck B, which is usually done by removing the belt 11, and then to remove the mining machine from the truck, and this latter is accomplished by properly setting two of the 55 jacks or posts 17 and leading ropes therefrom to the winches 13 upon the cross shaft 8. This having been done, the motor of the mining machine is started and through the gearing 9 the shaft 8 is rotated in proper direction to wind up the rope and drag the

mining machine bodily from off the truck and on to the floor or bench of the mine chamber. This will result in moving the mining machine to the position indicated in full lines in the chamber A'. It is next necessary to move the machine from this position to the position indicated in dotted lines in chamber A' where the first cut is to be made. To secure this movement of the machine, by means of its own motor, one of the jacks or posts 17 is set in the corner of the mine chamber and a rope 18 is led therefrom past a guide pulley 14 and to one of the winches 13. The motor being started and the shaft rotated, the mining machine will be dragged diagonally across the chamber toward the position indicated in dotted lines. It may be properly set in working position by employing a pair of jacks or posts set as indicated, and two ropes 18, the movement then being similar to that which is indicated in the chamber A for hauling the machine off the truck. 70 75 80 85

After the first cut has been made, the machine is moved transversely across the face of the wall of coal, the arrangement of jack and rope for this purpose being that indicated in the chamber A'. The machine will be moved step by step from the position indicated in full lines in this chamber to that indicated in dotted lines, which is the position of the final cut. The last cut having been made, and it being desired to move the machine back to position for loading upon the truck, the parts are arranged as shown 90 95 100 in chamber A'. 105

It will be understood that the guide pulleys 14 are adjusted from one position to another as may be required to cause the machine to move in the desired direction.

By means of the apparatus I have described it is possible to easily shift a heavy mining machine from one position to another within a low chamber, where it would be exceedingly difficult by the ordinary 110 methods to move it.

It will be observed that the rope winding and guiding devices for shifting the mining machine are located upon the bed frame, so that the strains incident to shifting the machine, as described, are taken thereby instead of by the moving frame that carries the cutters and motor, the advantage of which arrangement will at once be apparent to those familiar with machines of this kind. 115 120 125 130

While I have shown and particularly referred to a mining machine of the breast type it will be understood that my invention so far as it involves the adjustable cable guides is equally applicable to machines of other types. I believe myself to have been the first to provide in a machine of this general character a cable guide which is adjustable to vary the line of draft. The machine shown is adapted only for undercut-

ting the coal heading, but it will be understood that my invention, so far as it involves the relatively movable cutting mechanism, is equally applicable to any mining machine which comprises a main bed frame and a cutter frame movable bodily with respect thereto. I believe myself to have been the first to provide in a mining machine the combination of power means on the machine 5 for moving the cutter frame forward to effect cutting, and power means on the machine for moving the whole machine bodily laterally to bring it into a new cutting position.

10 15 What I claim is:

In a mining machine, the combination with a relatively smooth bottomed bed frame adapted to rest directly upon the

ground and to be freely moved in any direction, of a kerf cutting mechanism on the 20 bed frame operative when moved forward perpendicularly to a coal face, a cable adapted to be anchored externally of the machine, and mechanism on the machine for engaging the cable to guide and wind it, the 25 guiding parts of the said mechanism being bodily movable along lines substantially parallel to the lines of forward movement of the cutting mechanism to permit adjustment of the line of draft.

In testimony whereof I affix my signature, in presence of two witnesses.

GEORGE B. NORRIS.

Correction in Letters Patent No. 1,215,692.

It is hereby certified that in Letters Patent No. 1,215,692, granted February 13, 1917, upon the application of George B. Norris, of Columbus, Ohio, for an improvement in "Mining-Machines," an error appears requiring correction as follows: In the heading to the printed specification and the headings to the two sheets of drawings, the date of filing the application should be *December 18, 1905*, instead of "December 18, 1915"; and that the said Letters Patent should be read with this correction therein that the same may conform to the record of the case in the Patent Office.

Signed and sealed this 5th day of June, A. D., 1917.

[SEAL.]

F. W. H. CLAY,

Acting Commissioner of Patents.
